UNITED STATES PATENT OFFICE.

JACOB SOKOLOV, OF NEW YORK, N. Y., ASSIGNOR TO UNDERWOOD TYPEWRITER COMPANY, OF NEW YORK, N. Y., A CORPORATION OF DELAWARE.

STENCILING-MACHINE.

1,075,735.

Specification of Letters Patent. Patented Oct. 14, 1913.

Application filed June 28, 1912. Serial No. 706,334.

To all whom it may concern:

Be it known that I, JACOB SOKOLOV, a citizen of the United States, residing in the borough of Brooklyn, New York city, in the 5 county of Kings and State of New York, have invented certain new and useful Improvements in Stenciling-Machines, of which the following is a specification.

This invention relates to stenciling machines, more particularly to machines of 10 this character which are provided with means for handling the freshly stenciled sheets or copies, so as to prevent their smudging or offsetting.

15 In the usual type of stenciling or duplicating machine, the stencil is mounted upon a perforated cylinder to the interior of which is applied a heavy ink which flows through the cylinder perforations and 20 through the character perforations of the stencil onto the copy as the latter is pressed against the cylinder and fed past the same. To prevent the smudging or offsetting of 25 the copies after receiving the impression from the stencil, it has been proposed to provide a movable web or ribbon of material upon which the copies are to fall as they are discharged from the stencil cylinder. The web and copies are then to be rolled 30 together upon a reel, thus drying the copies out of contact with one another, after which the reel is reversed so as to discharge the dry copies from the machine.

When discharging the dried copies, the 35 ink from the stencil cylinder is apt to drop and smear the copies or the drying web. Particles of dust or grease are also liable to fall down upon the table and soil the copies. A plan has been proposed whereby the reels 40 are shifted so as to turn them into reverse positions, whereby the movement of the web discharges the sheets away from the stencil cylinder. With this construction it is also necessary to disconnect the driving mechanism which drives the reel from the stencil cylinder, and this involves loss of time. Moreover, in constructions in which the reel 45 is moved relatively to the stencil cylinder, it is not convenient to use a positive drive, such as a gear drive, which is certain in operation and does not need adjustment.

The primary object of this invention is to 50 overcome the difficulties above stated, and to this end I gear the reel directly to the stencil cylinder, and for adjusting the apparatus for discharging the dry sheets, I

provide simple mechanism which can be operated very quickly and easily without necessitating the shifting of the reels in any way. I mount an adjustable roller adjacent to the web, which roller is adapted to shift the web from a position below the reel, wherein it feeds the copies to be rolled upon the reel, to a position above the reel. In the latter position, reverse rotation of the reel 60 and web causes the sheets to be discharged over the reel free from the machine without passing back to the stencil cylinder. To prevent the cylinder from rotating the reel backward when the former is moved back, 65 as when it overruns its position as determined by the stop, I provide a ratchet clutch in the train of gears connecting the stencil cylinder with the reel. This clutch may be entirely thrown out of operation when the 70 rotation of the reel is reversed for the purpose of discharging the dry copies therefrom. Both of these adjustments are very simple and easy to make and require very little time, and thus the dry sheets can be 75 quickly discharged from the machine in a position where all smudging or soiling of the sheets is avoided.

Other objects and advantages will herein-after appear.

In the accompanying drawings, Figure 1 is an elevation of my improved stenciling machine. Fig. 2 is a plan thereof partly in section. Fig. 3 is a section taken along lines 3-3 of Fig. 2. Fig. 4 is a sectional elevation illustrating the position of parts when adjusted for discharging the dry sheets. Fig. 5 is a detail view illustrating the gear and pin in driving engagement with the gudgeon on the reel. Fig. 6 is a detail view 90 illustrating the gear and pin in a position of disengagement with the gudgeon. Fig. 7 is a fragmentary detail view illustrating the hub of the gear wheel with the aperture for receiving the projection on the finger-piece. Fig. 8 is a sectional detail view illustrating the ratchet clutch in inoperative position. Fig. 9 is a perspective detail view illustrating the spool with the end plate detached.

The sheets 1 are fed to the stencil cylinder 2 from table 3 and receive the impression of the stencil to which they are pressed by the pressure roll 4. The stencil cylinder is rotated by means of a handle 5 in the direction of the arrow shown in Fig. 1; and the sheets are discharged upon a web or

ribbon of absorbent material 6 carried by a spool 7 mounted adjacent the stencil cylinder. A reel 8, of construction substantially similar to spool 7, is mounted on the frame 15 of the machine a short distance farther from the stencil cylinder and on the same side thereof with the spool. This reel is geared to the stencil cylinder shaft and as the latter is rotated it drives the reel upon 20 which are rolled the web with the stenciled sheets or copies carried thereon.

When the web on the spool has been entirely rolled on the reel, or at any other time when it is desired to discharge the 25 sheets which have been dried on the reel by reason of their contact with the absorbent web, the mechanism for driving the reel from the stencil cylinder is thrown out of operation and the reel is rotated in the reverse direction so as to discharge the sheets, 30 free from the machine. This is accomplished as follows: Pivoted coaxially with the reel 8 are a pair of arms 9 carrying a roll 10 beneath the web. These arms have an extension 11 on the opposite side of their pivots and one of these is formed with an 35 aperture 12 into which is projected by a spring 13 a detent 14 mounted in a suitable housing 15 on the frame. The arms may be adjusted so as to lift the web to a 40 position above the reel, in which position the arms are held by the detent. The spool 7 is then rotated by a handle 16 in the direction of the arrow shown in Fig. 4 so as to wind the web thereon. This web accordingly unwinds from the reel 8 and by reason of the arrangement of the web above the reel the sheets are discharged over the latter free from the machine.

Pressure is applied to the web, as it is rolled on the reel together with the sheets, by means of a pressure roll 17 mounted on a pair of arms 18 fixed to a shaft 19 journaled in the frame. Shaft 19 has fixed thereto adjacent its ends a pair of arms 20 which are held yieldingly inward by means of springs 21 attached at one end to pins 22 carried by the arms and at the other end to pins 23 fixed to the frame.

To drive the reel from the stencil cylinder the latter has connected thereto a bevel gear 24 meshing with a bevel pinion 25 coupled to one end of shaft 26. The latter has adjacent to its other end a muff 27 fixed thereto extending loosely over a sleeve 28 fixed to a stub shaft 29 journaled in a bracket 29^a and having a bevel pinion 30 fixed thereto. Slidably mounted within the muff is a sleeve 31 having ratchet teeth 32 adapted to engage ratchet teeth 33 on sleeve 28 to which it is impelled by a spring 34 carried in the muff. A pin 35 formed with a finger knob projects from sleeve 31 through a slot 36 which extends longitudinally of the shaft. When the stencil cyl-

inder is rotated in the direction to feed a sheet out, the ratchet teeth of the sleeve 31 engage the teeth of sleeve 28 to rotate the same, which in turn transmits the motion to the reel 8. When the stencil cylinder is 75 rotated in the opposite direction, the teeth on sleeve 31 slip past the teeth on sleeve 28 and said sleeve 31 slides back and forth on the shaft, and the pin 35 works back and forth in the slot 36.

To render the clutch inoperative, the pin 35 is grasped and pulled inward until it is brought in the transverse portion 37 of slot 36. In this position the pin holds the sleeve 31 in inoperative position against the tension 80 of the spring. The pinion 30 meshes with a bevel gear 38 having a sleeve 39 journaled in the frame in axial alinement with the open bearing 40 which carries one of the gudgeons 41 extending from the reel 8. A pin or plunger 42 slides in an axial bore in said bevel gear 38 and is impelled by a spring 43 inwardly to seat in a recess 44 in the gudgeon 41. A key 45 is attached to the pin and slides in a slot 46 in the hub of the 85 gear and is adapted to be slid into the slot 47 in the gudgeon 41 when the pin 42 seats in the recess 44, thus coupling the gear to the reel. The pin may be held out of engagement with the gudgeon by grasping the 90 finger piece 48, which is rotatably mounted on the end of the pin, and pulling the pin outward against the tension of the spring until the stop 49 is pulled out from the aperture 50 in the hub of the gear wheel, and then rotating the finger piece until the stop 95 engages the outer face of the hub. The opposite end of the reel 8 also has a gudgeon 41^a mounted in the open bearing 40^a. This gudgeon has a recess 44^a in which seats a 100 pin or plunger 42^a. When the pins are retracted outward the reel is free to be lifted off from the open bearings. The spool 7 also has gudgeons 51 and 51^a extending 105 thereto at its ends which are mounted in open bearings 52 and 52^a. Pins 53 and 53^a are slidably mounted in the frame axially of said gudgeons and seat in recesses formed 110 therein. The pin 53^a has attached thereto the handle 16 and has also a projection or key 55 which registers with slot 56 formed in the gudgeon 51^a. The spool is thus held 115 in position in its bearings and has the handle 16 coupled thereto. When the pins are retracted, the spool may be lifted off its 120 bearings similarly to the reels. All of the pins engaging the gudgeons may if desired be supplied with finger pieces 48^a and stops 125 similar to the finger piece 48, and stop 49 for the pin 42. These stops may seat in recesses similar to the aperture 50 illustrated in Fig. 7. All of the pins may thus be held out of engagement while the reel and spool are 130 being lifted off their bearings.

As illustrated in Figs. 2 and 9 the spool

or reel consists of shaft 57 having at one end a plate 58 attached thereto having a cylindrical flange 59 extending inwardly therefrom. At the other end the shaft is formed with a collar 60, having a headed pin or screw 61 on its side face. An end plate 62 having an inwardly extending flange 63 and a central aperture 64 is mounted on the gudgeon at the end of the shaft 10 against the collar. A slot 65 is formed in the plate having an enlarged portion 66 through which the head of the pin may pass. When the end plate 62 is inserted on the gudgeon and rotated, it is locked in position upon the shaft by the screw 61. The spool or reel 15 may thus be assembled or detached for replacing the web of absorbent material.

As above stated the spool and reel are of substantially similar construction, the distinguishing terms being adopted for the sake 20 of clearness in referring to these members.

Variations may be resorted to within the scope of the invention, and portions of the improvements may be used without others.

Having thus described my invention, I claim:

1. In a stenciling machine, a stencil cylinder, a spool mounted adjacent thereto, said spool carrying a ribbon or web of absorbent material upon which the stenciled sheets fall, a reel for rolling thereon the web together with the stenciled sheets, and means for laterally shifting the web with reference to said spool and reel whereby reverse rotation of the spool discharges the stenciled sheets from the reel.

2. In a stenciling machine, a stencil cylinder, a spool mounted adjacent thereto, said spool carrying a ribbon or web of absorbent material upon which the stenciled sheets fall, a reel for rolling thereon the web together with the stenciled sheets, and an arm for lifting the web whereby reverse rotation of the spool discharges the stenciled sheets 45 from the reel.

3. In a stenciling machine, a stencil cylinder, a spool mounted adjacent thereto, said spool carrying a ribbon or web of absorbent material upon which the stenciled sheets fall, a reel for rolling thereon a web together with the stenciled sheets, an adjustable arm for lifting the web whereby reverse rotation of the spool discharges the stenciled sheets 50 from the reel, and means for holding the arm in adjusted position.

4. In a stenciling machine, a stencil cylinder, a spool mounted adjacent thereto, said spool carrying a ribbon or web of absorbent material upon which the stenciled sheets fall, a reel rotated from the cylinder for rolling thereon the web together with the stenciled sheets, means for uncoupling said 60 rotating means, and means for laterally shifting the web with reference to said spool and reel whereby reverse rotation of the spool and reel 65 whereby reverse rotation of the spool discharges the stenciled sheets from the reel.

spool discharges the stenciled sheets from the reel.

5. In a stenciling machine, a stencil cylinder, a spool mounted adjacent thereto, said spool carrying a ribbon or web of absorbent material upon which the stenciled sheets fall, a reel rotated from the cylinder for rolling thereon the web together with the stenciled sheets, means for uncoupling said rotating means, and an arm for lifting the web whereby reverse rotation of the spool 70 discharges the stenciled sheets from the reel.

6. In a stenciling machine, a stencil cylinder, a spool mounted adjacent thereto, said spool carrying a ribbon or web of absorbent material upon which the stenciled sheets fall, a reel rotated from the cylinder for rolling thereon the web together with the stenciled sheets, means for uncoupling said 80 rotating means, an adjustable arm for lifting the web whereby reverse rotation of the spool discharges the stenciled sheets from the reel, and means for holding the arm in adjusted position.

7. In a stenciling machine, a stencil cylinder, a spool mounted adjacent thereto, said spool carrying a ribbon or web of absorbent material upon which the stenciled sheets fall, a reel for rolling thereon the web together with the stenciled sheets, and an arm mounted coaxially with the reel for lifting the web whereby reverse rotation of the spool 95 discharges the stenciled sheets from the reel.

8. In a stenciling machine, a stencil cylinder, a spool mounted adjacent thereto, said spool carrying a ribbon or web of absorbent material upon which the stenciled sheets fall, a reel for rolling thereon the web together with the stenciled sheets, and a frame comprising a pair of arms mounted coaxially with said reel for lifting the web whereby reverse rotation of the spool 100 discharges the stenciled sheets from the reel.

9. In a stenciling machine, a stencil cylinder, a spool mounted adjacent thereto, said spool carrying a ribbon or web of absorbent material upon which the stenciled sheets fall, a reel for rolling thereon the web together with the stenciled sheets, means for applying pressure to the web upon the reel, and means for laterally shifting the web with reference to said spool and reel whereby reverse rotation of the spool 105 discharges the stenciled sheets from the reel.

10. In a stenciling machine, a stencil cylinder, a spool mounted adjacent thereto, said spool carrying a ribbon or web of absorbent material upon which the stenciled sheets fall, a reel for rolling thereon the web together with the stenciled sheets, a pair of arms carrying a roll adjacent to the reel, means engaging the arms for yieldingly holding the roll against the web on 115 120 125 130

the reel to apply pressure thereto, and means for laterally shifting the web with reference to said spool and reel whereby reverse rotation of the spool discharges the stenciled sheets from the reel.

11. In a stenciling machine, a stencil cylinder, a spool mounted adjacent thereto, said spool carrying a ribbon or web of absorbent material upon which the stenciled sheets fall, a reel for rolling thereon the web together with the stenciled sheets, a gear coupled to the stencil cylinder shaft, a gear coupled to the reel shaft, a transmitting shaft having gears thereon meshing with the above mentioned gears, a one-way clutch in said transmission train, and means for throwing said clutch out of operative engagement.
12. In a stenciling machine, a stencil cylinder, a spool mounted adjacent thereto, said spool carrying a ribbon or web of absorbent material upon which the stenciled sheets fall, a reel for rolling thereon the web together with the stenciled sheets, a gear coupled to the stencil cylinder shaft, a gear coupled to the reel shaft, a transmitting shaft having gears thereon meshing with the above mentioned gears, a one-way clutch on the transmitting shaft comprising a muff fixed to the shaft, a sleeve having ratchet teeth slidable in said muff, a toothed mem-

ber attached to one of the gears on the transmitting shaft, a handle on the sleeve projecting through a slot in the muff, and a spring for yieldingly holding the sleeve in engagement with the toothed member.

13. The combination of a stencil cylinder, a drying web arranged at the delivery side of the stencil cylinder to receive the stenciled sheets therefrom, a reel upon which the web and sheets are wound, the web running to the under side of said reel, and a web guide shiftable to carry said web above said reel to cause the dried sheets to discharge from the reel when the rotation of the same is reversed.

14. The combination of a stencil cylinder, a reel having a driving connection to said stencil cylinder, a web-carrying spool between said reel and said cylinder, the web running from the upper side of said spool to the lower side of said reel in position to receive the sheets from the stencil cylinder, means for turning the spool to rewind the web thereon, and a web guide shiftable to carry the web above the reel to cause the dried sheets to discharge from the top thereof.

JACOB SOKOLOV.
